PAPER BAG HAVING FLAP WITH REINFORCED LOCKING TONGUE AND TICKET RETAINER

George W. Poppe, Brooklyn, N. Y., assignor to
Equitable Paper Bag Co. Inc., Long Island City,
N. Y., a corporation of New York

Application April 29, 1952, Serial No. 284,965

6 Claims. (Cl. 229—84)

1

This invention relates to a paper bag having a flap provided with a reinforced locking tongue and providing an arrangement whereby a ticket, memorandum or the like, folded in strip form, may be secured to the bag without the need for using a common pin or the like with their attendant disadvantages.

One object of the invention is to provide a paper bag which may be manufactured at a cost substantially the same as a conventional paper bag yet which will have the advantages indicated, namely, a reinforced flap locking tongue and an arrangement for securing the ticket or memorandum strip or the like to the bag through using the construction of the bag itself. Another object is to provide for securing the described strip to the bag in such a way that one or both sides of the strip are visible.

Specific examples of the invention incorporated into an otherwise conventional flat paper bag, are illustrated by the accompanying drawings in which:

Fig. 1 is a back view of the bag;

Fig. 2 is a front view showing only the top portion of the bag;

Fig. 3 is the same as Fig. 2 excepting that it shows the bag prior to closing of its mouth and in the form that the bag is usually sold;

Fig. 4 is a cross section taken on the line 4—4 in Fig. 1;

Fig. 5 is a cross section taken on the line 5—5 in Fig. 2;

Fig. 6 is a perspective showing the action of the flap lock;

Fig. 7 shows the top portion only of the front side of a second example of the bag;

Fig. 8 shows the back side of the bag of Fig. 7;

Fig. 9 is a cross section taken on the line 9—9 in Fig. 7;

Fig. 10 is a cross section taken on the line 10—10 in Fig. 7;

Fig. 11 is a cross section taken on the line 11—11 in Fig. 7;

Fig. 12 is a perspective showing the action of the details of the invention incorporated by this second example; and

Fig. 13 is similar to Fig. 7 excepting that it shows the second example in the form in which it is usually sold and prior to folding of any of the parts.

Referring to the first example shown by Figures 1 through 6, the illustrated bag has a front wall 1 and a back wall 2 which are mutually opposed and define a mouth, a flap 3 extending from the back wall 2 and being foldable down

over the other or front wall 1 to close the bag mouth.

Both bag walls are severed along an upwardly facing U-shaped line 4 to define upwardly swinging tongues 5 which when displaced by being folded, along their fold lines 6, provide the bag walls with an opening.

The flap 3 includes the longitudinal seam 7 of the bag wall 2 and throughout the flap this is left disconnected, by interrupting the usual lines of adhesive, so that the flap includes a right-hand section, numbered 3, and a left-hand section numbered 3a. This left-hand section has a transverse or horizontal fold line 8 on which the flap section 3a folds doubled on itself, the flap parts being long enough so that the flap section 3a overlaps the opening formed by folding and displacing of the wall tongues 5.

As shown by Fig. 3 in particular, the flap section 3a is severed along lines 9 defining a foldable tongue 10, at the flap fold line 8, when the flap section 3a is folded double on this line. This flap 10 is located, by proper placement of the severance lines 9, to pass through the described wall opening when the tongue 10 is folded. The flap tongue lines of severance 9 comprise substantially C-like shapes spaced transversely respecting the flap and facing each other and forming the tongue 10 into a winged tongue wider than the described wall opening when the flap section 3a is doubled on its fold line 8.

In using this bag the merchandise or the like is placed in the bag while the latter is in the condition shown by Fig. 3. If desired the right-hand flap section 3 may be folded down inside of the bag mouth as shown by Fig. 2. In any event the flap section 3a is folded double on its fold line 8 so that the lines of severance 9 define the tongue 10. Note that this tongue is reinforced without the use of reinforcing patches or the like, because the tongue is formed from a double thickness of the flap section 3a.

Displacement of the tongues 5 in either direction forms the bag wall opening, and the tongue 10 may then be thrust through this opening so that its wing-like transverse ends snap on the other side of the bag and lock the tongue 10 against withdrawal. As shown by Fig. 6 a single push of the tongue 10 causes this tongue to displace the wall tongues 5 and effect the locking action. This is not only simple and convenient but it has the advantage that the resiliency of the tongues 5 holds down the tongue 10 so that its wings more positively retain their locked relationship.

All of the above features are provided without adding anything to what may be an otherwise conventional flat paper bag. Although the flap locking tongue is reinforced, no extra pieces of paper in the form of patches or the like are required. Thus this invention achieves its stated objectives in so far as the provision of a reinforced flap locking tongue without increase in cost, is concerned.

Going now to the second example, shown by Figures 7 through 13, it will next become apparent how the principles of the invention provides for retaining a ticket strip or the like to the bag so that both sides of the strip are visible.

In so far as is possible the same numerals are applied to corresponding parts, of this second example, as were used in connection with the first example. The letter *a* is added as required for identification purposes.

It will be noted that the flap, necessarily marked 3b, is formed as a single flap by reason of the longitudinal bag seam being secured throughout the flap. The tongue 5a is shifted to the center of the bag walls by appropriate placement of the lines of severance 4a. The tongue 10a is correspondingly shifted in the same fashion so that it may be passed through the opening formed by displacement of the tongue 5a. In both examples the tongues 10 and 10a respectively, of course, hinge on their own fold lines, indicated at 11 in Fig. 3 and 11a in Fig. 13 in the case of the first and second examples respectively.

Coming now to the ticket. This, or any other memorandum or piece of paper, is folded into the form of a strip 12 of any desired length providing it is longer than the width of the tongue 10a. Thus folded, the ticket is woven through the lines of severance 9a of the tongue 10a so that, with the flap opened, the strip ends are on the inside of the flap while the central portion of the strip is on the outside of the part that forms the tongue 10a. Furthermore, the strip 12 is arranged with its upper edge flush with the flap fold line 8a so that when the flap is folded double on itself this strip is nested in the flap fold line and inside of the doubled flap. Then, with this arrangement, the previously described operations are performed. In other words, the tongue 10a, formed by folding of the flap, is thrust through the opening formed by displacement of the tongues 5a. Thus the bag flap is locked shut with the ticket strip secured to the bag flap and exposed at the front of the bag because the ticket strip spans between the lines of severance 9a as is shown by Fig. 7.

As to the opposite side of the ticket strip, this also is exposed at the back of the bag when the tongue 10a is folded upwardly as shown by Fig. 8. In the first example the tongues 5 were swung with the tongue 10, but in this second example the tongues 5a are shown as being first folded up against the front wall 1a of the bag, the tongue 10a then being thrust through the resulting opening to the back of the bag and folded upwardly as described. The finished result has the appearance of a bag provided with back and front windows through which the ticket strip is visible through both directions, both sides of the strip being exposed throughout the strip's central portion. The cross sections, particularly Fig. 11, help to understand the described arrangement.

It can now be seen that the described bag construction attains all of the objectives of the invention. Whether the described construction is

used simply as a reinforced flap lock or also to retain the ticket strip, there is no need for adding parts to the conventional bag construction or otherwise altering its manufacture excepting for the provision of the appropriately placed lines of severance. These lines may be made by the use of a suitable die cutter roller set used in conjunction with the usual automatic paper bag making machine. This does not add appreciably to the cost of the final product.

I claim:

1. A bag having opposed walls defining a mouth and a flap extending from one of the walls and foldable down over the other wall to close the mouth, the bag walls having an opening and the flap having a transverse fold line on which the flap folds double on itself and the flap being long enough to overlap the opening when the flap is thus doubled, the flap being severed along lines defining a foldable tongue at the flap fold line and located to pass through the wall opening when the tongue is folded.

2. A bag having opposed walls defining a mouth and a flap extending from one of the walls and foldable down over the other wall to close the mouth, the bag walls having an opening and the flap having a transverse fold line on which the flap folds double on itself and the flap being long enough to overlap the opening when the flap is thus doubled, the flap being severed along lines defining a foldable tongue at the flap fold line and located to pass through the wall opening when the tongue is folded, the flap tongue lines of severance comprising substantially C-like shapes spaced transversely respecting the flap and facing each other and forming a winged tongue wider than the wall opening when the flap is doubled on its fold line.

3. A bag having opposed walls defining a mouth and a flap extending from one of the walls and foldable down over the other wall to close the mouth, the bag walls having an opening and the flap having a transverse fold line on which the flap folds double on itself and the flap being long enough to overlap the opening when the flap is thus doubled, the flap being severed along lines defining a foldable tongue at the flap fold line and located to pass through the wall opening when the tongue is folded, a strip-like ticket and the like being woven through the flap lines of severance and nested in the folded flap and thus retained to the bag.

4. A bag having opposed walls defining a mouth and a flap extending from one of the walls and foldable down over the other wall to close the mouth, the bag walls having an opening and the flap having a transverse fold line on which the flap folds double on itself and the flap being long enough to overlap the opening when the flap is thus doubled, the flap being severed along lines defining a foldable tongue at the flap fold line and located to pass through the wall opening when the tongue is folded, the flap tongue lines of severance comprising substantially C-like shapes spaced transversely respecting the flap and facing each other and forming a winged tongue wider than the wall opening when the flap is doubled on its fold line and the winged tongue being folded through the wall opening with the tongue wings locked with the opposite wall, and a ticket strip being nested inside of the folded flap adjacent to its fold line and woven through the flap tongue lines of severance, the folded flap tongue forming an

opening through which the ticket strip is visible.

5. A bag having opposed walls defining a mouth and a flap extending from one of the walls and foldable down over the other wall to close the mouth, the bag walls having an opening and the flap having a transverse fold line on which the flap folds double on itself and the flap being long enough to overlap the opening when the flap is thus doubled, the flap being severed along lines defining a foldable tongue at the flap fold line and located to pass through the wall opening when the tongue is folded, the flap tongue lines of severance comprising substantially C-like shapes spaced transversely respecting the flap and facing each other and forming a winged tongue wider than the wall opening when the flap is doubled on its fold line, the flap being folded double on its fold line and the winged tongue being folded through the wall opening with the tongue wings locked with the opposite wall, and a ticket strip being nested inside of the folded flap adjacent to its fold line and woven through the flap tongue lines of severance, the folded flap tongue forming an opening through which the ticket strip is visible, the bag wall opening being defined by lines of severance through the bag walls defining tongues having top fold lines on which the tongues are folded

up under the flap, the tongues being formed from the two bag walls and locking the same together.

5. A bag having opposed walls defining a mouth and a flap extending from one of the walls and foldable down over the other wall to close the mouth, the bag walls having an opening and the flap having a transverse fold line on which the flap folds double on itself and the flap being long enough to overlap the opening when the flap is thus doubled, the flap being severed along lines defining a foldable tongue at the flap fold line and located to pass through the wall opening when the tongue is folded, the bag wall opening being defined by lines of severance through both walls defining upwardly folding tongues formed by the two bag walls.
